UNITED STATES PATENT OFFICE.

SETH H. LEAVENWORTH, OF CINCINNATI, OHIO, ASSIGNOR TO THE HOMAN SILVER PLATE COMPANY, OF CINCINNATI, OHIO, A CORPORATION OF OHIO.

DESIGN FOR A COFFEE-POT OR SIMILAR VESSEL.

SPECIFICATION forming part of Design No. 35,800, dated March 11, 1902.

Application filed November 4, 1901. Serial No. 81,160. Term of patent 7 years.

To all whom it may concern:

Be it known that I, SETH H. LEAVENWORTH, a citizen of the United States of America, and a resident of Cincinnati, in the county of Hamilton and State of Ohio, have invented and produced a certain new and original Design for a Coffee-Pot or Similar Vessel, of which the following is a specification.

Figure 1 is a perspective view of a tea or coffee pot embodying my invention. Fig. 2 is a sectional view of the same, taken upon line $\alpha\alpha$ of Fig. 1.

The lower enlarged portion a of the vessel is substantially semispherical. Above portion a is a conical portion a' , which terminates in a reduced neck a^2 .

The principal features of my design are a

series of diametrical grooves a^3 , dividing the surface of portion a into a series of convex sections a^4 , a series of raised ribs a^5 in conical portion a' in alinement with grooves a^3 and dividing conical portion a' into a series of concave sections a^6 , and a raised ornamental ridge a^7 , composed of parts of circles upon the meeting lines of the convex sections with the concave sections.

What I claim is—

The design for a coffee-pot or similar vessel as herein shown and described.

SETH H. LEAVENWORTH.
